tion of Michigan
Filed Mar. 1, 1965, Ser. No. 435,866
3 Claims. (Cl. 15—230.14)

ABSTRACT OF THE DISCLOSURE

A finger type buffing wheel in which each of the fingers has a core and a wrapper covering the core with the wrapper having a flap overlapping an adjacent finger with the fingers being connected by stitching extending through the core and the wrapper.

The present invention relates to buffing wheels, and more particularly to buffing wheels of the finger type.

In the past, finger type buffing wheels have been constructed with the fingers secured together at their radially inner ends and with the fingers being maintained separately from each other in a radially outward direction such that the individual fingers can flex independently of one another (i.e., as for example in the patent to Churchill No. 2,724,937). With such flexibility, however, the cutting action of the wheel is somewhat impeded since there is a tendency to perform the work along the sides of the fingers rather than at the peripheral radially outer edge. It is an object of the present invention to provide an improved finger type buffing wheel in which the work is performed substantially at the radially outer peripheral edges of the fingers.

It is another object of the present invention to provide a finger type buffing wheel having an improved cutting action.

Other objects, features, and advantages of the present invention will become apparent from the subsequent description and the appended claims, taken in conjunction with the accompanying drawings, in which:

FIGURE 1 is a side elevational view of a finger type buffing wheel embodying the features of the present invention;

FIGURE 2 is a fragmentary, enlarged, sectional view of the wheel of FIGURE 1 taken substantially along the line 2—2;

FIGURE 3 is a partial view, similar to that of FIGURE 1, of the finger type buffing wheel of FIGURE 1 prior to final connection of the individual fingers;

FIGURE 4 is an enlarged fragmentary view of the portion of the wheel of FIGURE 3 generally enclosed within the dot-dash line indicated by the numeral 4; and

FIGURE 5 is a sectional view of the finger type buffing wheel taken along the line 5—5 in FIGURE 4.

Considering first the construction of the buffing wheel prior to assembly, and looking now to FIGURES 3—5, a finger type buffing wheel is generally indicated by the numeral 10 and includes a plurality of identical fingers 12 which are secured at one end to a generally annular retainer ring 15 so as to extend radially outwardly therefrom and to be spaced circumferentially thereabout. As can be seen from FIGURE 5, two side-by-side rows of fingers 12 are provided. Each of the fingers 12 is constructed with a core 14 which, in the preferred form, is made up of a plurality of individually twisted sisal fibers or cords which are generally twisted about each other in a manner as shown in FIGURE 4. Other types of materials or fibers may be utilized. The core 14 is encased in a cloth wrapper 18 which is made from a flat piece of material sewn as along the line 20 to thereby longitudinally cover the core 14. The wrapper can be made of cot-

ton or other suitable material. For a purpose to be presently understood, the wrapper 18 is provided with an excess of material to define a flap 22 which extends generally circumferentially from one end of the case 18. Note that all of the flaps 22 extend generally in the same direction and are located at the same side of the fingers 12.

As shown in FIGURES 3, 4 and 5, the fingers 12 are secured together at their radially innermost ends by the annular retainer ring 15 and at this stage in the construction are individually flexible. However, in order to provide for more aggressive cutting or working action and in order to provide that the work be performed at the radially outer peripheral edge of the buffing wheel 10, the individual fingers 12 are sewn together in the manner as shown in FIGURES 1 and 2 by means of a spiral stitch 24 which commences proximate the ring 15 and terminates near the outer ends of the fingers 12; thus the adjacent ones of the fingers 12 are held together for substantially their entire lengths. Note that the flaps 22 of adjacent fingers 14 overlap adjacent fingers such that the stitching will occur not only through the core 14 for each of the individual fingers 12, but also through the flaps 22 of the adjacent fingers 12. The flap 22 therefore provides means whereby a good stitching bond can be maintained between adjacent fingers 12. If the flaps 22 were not provided, the individual fingers would be held together generally only by the stitching thread overlapping adjacent fingers 12. It can be appreciated that, with the construction as shown in FIGURES 1 and 2, a strong connection is provided between adjacent fingers 12. Note also that the additional bulk provided by the flaps 22 is useful, since the flaps 22 in the preferred form would be a cotton fabric and hence be substantially more absorptive than the sisal cord whereby more working compound could be held by the work wheel 10.

It should be noted that while the individual fingers 12 are stitched together, they are stitched at spaced intervals as indicated by the spiral stitch 24 and hence a degree of individual flexibility is still maintained. It can be appreciated, however, that the stiffness of the wheel in general has been increased over a finger type buffing wheel in which the fingers are free to move independently of each other and, in this regard, it should also be noted that the individual rows of fingers 12 cannot move or split away from each other in an axial direction, thereby further encouraging the working of the wheel 10 to occur at the outer edges of fingers 12.

While it will be apparent that the preferred embodiment of the invention disclosed is well calculated to fulfill the objects above stated, it will be appreciated that the invention is susceptible to modification, variation and change without departing from the proper scope of fair meaning of the subjoined claims.

What is claimed is:

1. A buffing wheel comprising: annular retainer means for securing a plurality of fingers, at least two rows of said plurality of individual fingers peripherally secured to said retainer means and circumferentially spaced thereabout and extending radially outwardly therefrom, each of said fingers comprising a longitudinally extending core formed of a plurality of strands and a wrapper longitudinally encasing said core, each said wrapper having a tubular portion enclosing said core and a flap extending circumferentially and located in general overlapping relation with an adjacent finger of the same row, each of said fingers of at least one of said rows having said flap extending circumferentially between adjacent rows, and means comprising stitching for securing adjacent ones of said finger together for substantially their entire lengths with said stitching connecting said flap and said adjacent ones of said fingers.

2. A buffing wheel comprising: annular retainer means for securing a plurality of fingers, at least two rows of said plurality of individual fingers peripherally secured to said retainer means and circumferentially spaced thereabout and extending radially outwardly therefrom, each of said fingers comprising a longitudinally extending core formed of a plurality of strands and a wrapper longitudinally encasing said core, each said wrapper having a tubular portion enclosing said core and a flap extending circumferentially between adjacent rows for substantially the length of said wrapper with said flap located in general overlapping relation with an adjacent finger of the same row, and means comprising circumferentially extending, radially spaced stitching for securing adjacent ones of said fingers together for substantially their entire lengths with said stitching connecting said flap and said adjacent ones of said fingers.

3. A buffing wheel comprising: annular retainer means for securing a plurality of fingers, at least two rows of said plurality of individual fingers peripherally secured to said retainer means and circumferentially spaced thereabout and extending radially outwardly therefrom, each of said fingers comprising a longitudinally extending core formed of a plurality of strands and a wrapper longi-

15

tudinally encasing said core, each said wrapper having a tubular portion enclosing said core and a flap extending circumferentially between adjacent rows for substantially the length of said wrapper with said flap located in general overlapping relation with an adjacent finger of the same row, and means comprising spirally, circumferentially extending stitching for securing adjacent ones of said fingers together for substantially their entire lengths with said stitching connecting said flap and said adjacent ones of said fingers, said stitching extending from a point proximate said retainer to a point proximate the radially outer edges of said fingers in a plurality of convolutions.
